CLAIM

The ornamental design for a brush with ergonomic handle,
as shown and described.

DESCRIPTION

FIG. 1 is a perspective view of our new brush with ergonomic handle;

FIG. 2 is a right side elevational view thereof, the left side
being a mirror image thereof;

FIG. 3 is a top plan view thereof;

FIG. 4 is a bottom plan view thereof;

FIG. 5 is a front elevational view thereof; and,

FIG. 6 is a rear elevational view thereof.
